CAP FOR VALVE STEMS

Filed Jan. 21, 1918

FIG. 1

FIG. 2

FIG. 3

FIG. 5

FIG. 4

Inventor
Henry B. Mead

By *W. Chlunstan*,
his Attorney

UNITED STATES PATENT OFFICE.

HENRY B. MEAD, OF CLEVELAND, OHIO.

CAP FOR VALVE STEMS.

Application filed January 21, 1918. Serial No. 213,036.

To all whom it may concern:

Be it known that I, HENRY B. MEAD, a citizen of the United States, residing at Cleveland, in the county of Cuyahoga and State of Ohio, have invented certain new and useful Improvements in Caps for Valve Stems, of which the following is a specification.

This invention relates to caps for protecting and excluding dust from the valve stems of pneumatic tires, and has for its main object to provide a cap which is easily and quickly attached to or detached from the valve stem without the necessity of turning it off the usual long threaded part of the same.

Another object of the invention is to provide a cap having a slidable member which is adapted to securely lock the cap to a valve stem and permit its ready removal.

With the above and other objects in view as will be understood, the invention will be hereinafter fully described with reference to the accompanying drawings, which illustrate a preferred embodiment thereof, and the novel features of the invention will be particularly pointed out in the appended claims.

In the drawings like characters of reference designate corresponding parts.

Figure 1 is a sectional elevation of a cap constructed in accordance with my invention.

Fig. 2 is a similar view taken at a right angle to Fig. 1,

Fig. 3 is a cross section taken on line 3—3 of Fig. 1,

Fig. 4 is a perspective view of one of the spring clamps, and

Fig. 5 is the same view as Fig. 1 except that the sliding member is in its outward position.

Referring to the drawings, 1 represents the fragmental portion of a wheel felly, and 2 the washer which screws onto the valve stem and against the felly for holding the valve stem in place. Said washer is provided with a central neck 3, which is threaded on its outer periphery as indicated at 4.

50 The cap or casing 5 is of the ordinary style with an open end 6, which is adapted to fit against the washer 2, and a closed end 7. Within the casing 5, and fixed to the opposite sides thereof by rivets 8 or other suitable means, are a pair of spring clamps 9, which carry at their free ends semi-circular

plates 10, having their inner faces threaded as at 11, for engaging the threads of the neck 3. Said spring clamps are normally out of engagement with the neck 3, and for forcing the teeth thereof into locking engagement with the threads of the neck, a slideable member 12 is employed. This slideable member consists of a pair of legs 13, which are connected at one end by a yoke 14. The legs of the slideable member 12 are arranged to slide within the casing 5, between the spring clamps 9, and their free ends over the adjacent ends of the semi-circular plates 10 for forcing them toward one another and thereby causing them to engage the neck 3. In order that the free ends of the legs 13 may easily pass behind the semi-circular plates 10, the inner sides of said ends of the legs are beveled at 15 and the outer faces of said plates are cut on an inclination at 16. The slideable member 12 is actuated by means of a rod 17, which is fixed to the yoke 14, and slidably mounted in an opening 18 of the closed end 7 of the casing. The rod 17 terminates in a head 19 for convenience of operation.

When it is desired to attach the cap, the slideable member 12 is first withdrawn by pulling outwardly on the rod 17, which action draws the free ends of the legs 13 clear of the adjacent ends of the semi-circular plates 10 of the spring clamps and allows them to spring away from one another. The cap is then placed in position over the neck 3, as shown in Fig. 5, and the rod 17 forced inwardly. This causes the free ends of the legs 13 to pass back of the adjacent ends of the semi-circular plates 10, and thereby force them toward one another whereby their teeth 11 are made to lock into the threads of the neck 3. To detach the cap, it is only necessary to pull the rod 17 outwardly. The spring clamps 9 will return to their normal positions out of engagement with the neck 3, and the cap may be removed.

It will be understood that slight changes in the details of construction may be made within the scope of the claims.

Having fully described my invention, what I claim is:

1. A cap for valve stems comprising a casing, clamps arranged within the casing, movable means within the casing for actuating the clamps, and means extending through the top of the casing for actuating

- said movable means, substantially as described.
2. A cap for valve stems comprising a casing having an open end and a closed end, a pair of clamps arranged within the casing near its open end, means within the casing for actuating the clamps, and a rod projecting through the closed end of the casing for actuating said means for actuating the clamps, substantially as described.
3. A cap for valve stems comprising a casing, a pair of spring clamps having one of their ends attached to the inside of the casing, the free ends of the spring clamps terminating in semi-circular plates, a slideable member within the casing, the slideable member having a pair of legs adapted to engage said plates for forcing them into locking action, and a rod fixed to the slideable member and extending through the casing for actuating the slideable member, substantially as described.
4. In a cap for valve stems, the combination of a washer, having a threaded neck, a casing over the neck, a pair of spring clamps having one of their ends attached to the inside of the casing, the free ends of the spring clamps terminating in semi-circular plates, the semi-circular plates being provided with teeth adapted to engage said threaded neck, a slideable member within the casing, the slideable member having a pair of legs adapted to engage said plates for forcing them into locking action, and a rod fixed to the slideable member and extending through the casing for actuating the slideable member, substantially as described.
5. A dust cap having an open lower end adapted to be applied to a valve stem and comprising an outside tubular member, a pair of clamping jaws fixedly mounted with respect to said outside member, a second member having its lower portion entirely within the outside tubular member above the clamping portions of the jaws and slideable axially with respect to said outside tubular member thereby to effect operative and inoperative positioning of said clamp-
- ing jaws by a relative sliding movement between said members.
6. A dust cap having an open lower end adapted to be applied to a valve stem and comprising an outside tubular member, a pair of resilient jaws fixedly mounted with respect to said outside member, a second member having its lower portion entirely within the outside member above the clamping portions of the jaws and slideable axially with respect to said outside member thereby to effect contraction and release of said clamping jaws upon a relatively sliding movement between said members.
7. A dust cap having an open lower end adapted to be applied to a valve stem and comprising an outside tubular member, a pair of clamping jaws fixedly mounted with respect to said outside member, a second member having its lower portion entirely inside of the outside member and also having a portion extending through and beyond the upper end of the outside member said second member being slideable axially with respect to the outside member said jaws and second mentioned member having engaging portions thereby to effect movement to operative and inoperative position of said jaws by a relative sliding movement between said members.
8. A dust cap comprising an outside tubular member, a pair of clamping jaws mounted inside of and upon the said outside member, a second member having its lower portion entirely inside of the outside member said second member also having a portion extending through and beyond the upper end of the outside member said second member being slideable axially with respect to the outside member said jaws and second member having engaging parts whereby to effect movement of said jaws to operative and inoperative position by a relatively sliding movement between the said members.

In testimony whereof I affix my signature.

HENRY B. MEAD.
